CLAIM

The ornamental design for a container for use on a roof rack, as shown and described.

DESCRIPTION

FIG. 1 is a front end elevational view of a container for use on a roof rack, showing the present invention;

FIG. 2 is a right side elevational view of the container shown in FIG. 1;

FIG. 3 is a rear end elevational view of the container shown in FIG. 1;

FIG. 4 is a left side elevational view of the container shown in FIG. 1;

FIG. 5 is a top plan view of the container shown in FIG. 1; FIG. 6 is a bottom plan view of the container shown in FIG. 1;

FIG. 7 is a left side perspective view of the container shown in FIG. 1; and,

FIG. 8 is a right side perspective view of the container shown in FIG. 1.
